UNITED STATES PATENT OFFICE.

WILLIAM WALLACE GIBSON, OF ALAMEDA, CALIFORNIA.

MILL.

Application filed August 25, 1924. Serial No. 733,972.

This invention relates to improvements in ore grinding mills and one of its objects is to provide a multi-cylinder mill in which the cylinders revolve around a central axle instead of revolving on their own axes, with a result that the crushing elements used in the cylinders are carried higher and tossed over in curved paths giving a greater crushing effect with less wear on the cylinders and without the tendency of the crushing elements to creep, which tendency occurs where the cylinders revolve on their own axes.

Another object of the invention is to provide a multi-cylinder mill of the character described in which the cylinders are equidistantly spaced in an arcuate arrangement about a central axle so that a counterbalancing effect is provided which will reduce horse power required to effectively operate the mill and provide for operation of the mill by a belt drive arrangement instead of requiring employment of gears, thus making possible an operation of the mill on less power and at less cost.

A further object is to provide in a mill of the character described an ore feed manifold that automatically evenly loads the respective cylinders at all times and prevents clogging or jamming of the feed passages and an unbalanced condition in the mill.

The invention further has for one of its objects to provide a novel means for automatically classifying the ore, which classifier carries over-size material which will not pass through the screen back to the cylinders to be reground. By this arrangement, the mill may be constructed to crush, for example, from 8 to 100 mesh, without damage or injury to the screen or increasing the cost of construction and operation of the mill.

The mill of this invention in addition to the advantages above enumerated which it provides, is simple as to construction and arrangement, consists of comparatively few parts, is comparatively inexpensive, arranged so that worn or broken parts may be readily and easily replaced and is durable and reliable in its operation.

With the above mentioned and other objects in view, the invention consists in the novel construction and combination of parts hereinafter described, illustrated in the accompanying drawings, and set forth in the claims hereto appended, it being understood

that various changes in the form, proportion, size and minor details of construction within the scope of the claims may be resorted to without departing from the spirit or sacrificing any of the advantages of the invention.

Referring to the drawings:

Fig. 1 represents a side elevation of a mill constructed in accordance with the invention.

Fig. 2 represents a longitudinal sectional view of the mill of this invention.

Fig. 3 represents a rear elevation of the mill, parts being broken away and other parts being shown in section in order to show the arrangement and construction of the grizzly.

Fig. 4 represents a front elevation of the mill.

The embodiment of the invention illustrated in detail in the accompanying drawings includes a central shaft 1, journaled in suitable bearings 2 on standards 3, there being a pulley 4 fixed to one end of the shaft to provide for operation of the mill with a belt drive arrangement, not shown. At the other end of the shaft there is provided a right angularly extending scoop 5 adapted to pick up ore from a hopper, not shown, and convey it through a hollow feed portion 6 of the shaft to the distributor 7. The scoop 5 is removably fastened as at 8 to the end of the shaft. The portion 6 of the shaft is provided with internal screw threads 9 for facilitating the feed of ore to the distributor. This distributor in the present instance, comprises a plurality of radially extending feed tubes 10 of equal length, formed integral with the shaft and in communication with the portion 6 thereof. The outer ends of the tubes 8 are provided with flanges 11 which are bolted as at 12 to the ends of a plurality of crushing cylinders 13, in the present instance there being four of such cylinders shown. These cylinders are arranged in an arcuate series around the axle 2, in spaced relation to one another and to the axle so that the arrangement of the cylinders will serve as an effective counterbalance to assist in the operation of the mill.

Each cylinder is provided with an intake opening 14 in registration with one of the tubes 10 and is also provided with the usual liner 15, having an opening 16 registering

with the opening 14. The other end of each cylinder is provided with an annular flange 17 bolted onto a grizzly 18 in the form of a circular flat plate, which grizzly extends over the open ends of the several cylinders and is provided with an opening 19 centrally thereof, through which the shaft 1 extends. A flanged collar 20 on the shaft holds the grizzly and shaft in proper assembled relation. 5 Those portions of the grizzly which register with the cylinders are provided with a series of arcuate openings or slots 21 around the discharge openings 22, which latter are provided with internal screw threads 23 to urge an intake of ore. Balls or rods, or other crushing elements, in the present instance being shown as balls, designated 24, are mounted in each cylinder as is customary in the art. 10 Attached to the rear face of the grizzly is an angle iron ring 25 to which a circular screen 26 is bolted. A similar ring 27 is provided for the outer end of the screen. The inner end of the screen abuts the outer 15 face of the grizzly whereas the outer end of the screen is closed by an annular plate 27' bolted to the ring 27. The size of the mesh of this screen depends on the character of the work to be accomplished by the mill and 20 may be varied in view of the special construction of this invention, for example, from 8 to 100.

It will thus be seen that the mill may be readily and easily disassembled in units or 25 sections so that worn or damaged parts may be readily replaced.

A plurality of classifying members in the 30 form of scoops as shown at 28, are provided in the screen and act automatically to pick up the over-size ore particles within the screen and convey them back to the respective cylinders, there being one classifying scoop for each cylinder. These scoops are closed except where communicated with the 35 openings 23 in the grizzly and at their mouth ends, which latter are elongated and extend for the width or length of the screen so that as the material which does not pass through the screen is carried around the 40 screen it will be picked up in the open ends or mouths 29 of the scoops and by virtue of the inclined walls 30 of the scoops be gravitated into the openings 22 back to the respective cylinders of the mill, in order to 45 be reground.

The operation of the mill is as follows: The feed scoop 5 picks up the ore and delivers it into the screw feed portion 6 of the axle, from whence it passes through the 50 distributor tubes 10 into the respective cylinders 13. The tubes 10 are so arranged that like quantities of the ore are delivered to each cylinder and the balanced arrangement will therefore be maintained in the mill. As 55 the ore is delivered through the openings 14

and 16 into the cylinders, on rotation of the mill, the crushing elements 24 will be carried up and tossed over in curved paths so as to have an effective crushing action on the ore, much more so than is the case in mills where the cylinders turn about their own axes, this being particularly due to the fact that the crushing elements will not tend to "creep" and will be given a greater degree of movement. This arrangement therefore provides for a quicker and more effective crushing of the ore with less wear on the mill parts than is possible with mills having a crushing cylinder rotating on its own axis. 70 75 80

The equal distribution of the ore to the cylinders and balanced arrangement of the cylinders provides a counterbalancing action which will effect a saving in power required to operate the mill. 85

As the ore is crushed and fed through the open ends 21 of the grizzly into the screen 26, the finer particles desired will pass through the screen into a suitable container or otherwise collected, as desired. The over-size ore particles, that is, the particles which will not pass through the screen, will be carried around on the inner side of the screen and be picked up by the scoop members 29. These scoop members 29 because of the inclined walls 30 and their positions relative to the screen, will convey the over-size ore particles back through the screw feed opening 22 into the mill, where they will be recrushed. The operation repeating until the ore is crushed to the necessary fineness to screen. This arrangement provides for crushing ore at from 8 to 100 mesh without jamming, puncturing or otherwise damaging the screen, whereas in other mills 90 having peripheral discharge screens, such an arrangement would result in damage to the screens unless classifiers such as provided in this invention were employed. 95 100 105

The re-grinding of the over-size particles 110 as provided in this invention eliminating that objectionable condition known in the art as "sliming" and insures a product of uniform mesh. By renewing the classifier and screen and substituting a blank end, the mill may thus be connected into an ordinary "sliming" mill. 115 120

I claim:

1. An ore crushing mill comprising a plurality of crushing cylinders, a shaft around which said cylinders are arranged in equidistantly spaced relation to one another and to the shaft, means for attaching the cylinders to the shaft, means for rotating the shaft, a plurality of crushing members in each of the cylinders, an ore scoop attached to the shaft for picking up ore on rotation of the shaft and a plurality of ore feed tubes of equal length in communication with the scoop and said cylinders. 125 130

2. An ore crushing mill comprising a plurality of crushing cylinders revolvable about a central axis, means for so mounting said cylinders including a shaft having a hollow feed portion extending into it from one end, an ore scoop connected with and adapted to deliver ore into said feed portion, a plu-

rality of tubes of equal length extending from the feed portion of the shaft to and being in communication with certain ends ¹⁰ of the cylinders and a plurality of crushing members in each of the cylinders.

WILLIAM WALLACE GIBSON.
